UNITED STATES PATENT OFFICE.

JOHN C. REED, OF PITTSBURGH, PENNSYLVANIA, ASSIGNOR TO STANDARD SANITARY MANUFACTURING COMPANY, OF PITTSBURGH, PENNSYLVANIA, A CORPORATION OF NEW JERSEY.

MOLD-FORMER.

1,078,108.

Specification of Letters Patent.

Patented Nov. 11, 1913.

Application filed August 29, 1912. Serial No. 717,746.

To all whom it may concern:

Be it known that I, JOHN C. REED, residing at Pittsburgh, in the county of Allegheny and State of Pennsylvania, a citizen 5 of the United States, have invented or discovered certain new and useful Improvements in Mold-Formers, of which improvement the following is a specification.

My invention relates to the forming of 10 molds for cast metal bath tubs, having a coating of vitreous enamel, and provided with outstanding partition-wings, such as shown and described in my application Serial No. 717,745.

15 In the manufacture of cast metal bath tubs covered with a coating of vitreous enamel, the metal must be of substantially constant thickness throughout, for if the metal varies in thickness it will heat and cool unevenly in the process of enameling 20 and thereby cause cracks or crazes to appear in the enamel. For this reason it is desirable to form the wings, mentioned above, of substantially constant thickness 25 throughout, such thickness being substantially the same as that of the tub-body. In the ordinary practice of forming molds, it would be necessary, in order to provide a tub with integral wings of substantially 30 constant thickness, to remove the wing-forming portion of the pattern from the sand with great care and exactness. Otherwise, the parallel walls of the wing-forming cavity of the mold will be broken down or 35 otherwise rendered defective; and such injury may occur even when very unusual precautions are taken.

The object of my invention is to provide 40 a mold former, whereby partition wings of substantially even thickness throughout may, in a simple and practical manner be mechanically formed on the outside of bath tubs and integral therewith.

In the accompanying drawing, which 45 forms part of my specification, and wherein the preferred form of my invention is illustrated, Figure 1 is a top plan view of a mold former for the outside walls of a corner tub; Fig. 2 is a vertical sectional view 50 taken on the line II II, Fig. 1; and Fig. 3 is a transverse sectional view taken on the line III III, Fig. 1.

Like numerals are used to designate like parts.

The mold former shown herein consists of 55 a skeleton frame 1 and a pattern 2, supported by the said frame through an interposed jarring ring 3. The said frame has side walls 4, end walls 5, and a peripheral ledge 6 adapted to receive the said ring and 60 provided with lugs 7. The pattern 2, which is preferably made of cast metal, may be exteriorly of the desired form of the tub body; and, as shown herein, is formed for the outside walls of a corner tub such as 65 illustrated in Figs. 1 to 4 of my application, Serial No. 717,745. A supporting rib 8 is formed on the bottom portion of the tub body or pattern 2, and a rim 9 on the top of the tub body, one side and one end of 70 which rim is curved, while the opposite side and end of the rim has a horizontally disposed ledge 10 adapted to fit against or extend into corner-forming walls of a bath room.

75 In forming a mold from such a pattern, as thus far described, the usual practice is to place a suitable flask (not shown herein) around the pattern 2, such flask resting upon the top face 11 of the frame 1 and being 80 brought to proper relative position upon said frame by means of pins (not shown) which extend through holes 12 in the lugs 7. The two said members are then suitably clamped together. Sand is then placed in 85 the flask, and suitably packed between the inner wall of such flask and the pattern 2. After the mold is thus formed, the connection between the flask and frame 1 is released, the ring 3 is suitably jarred to 90 loosen the sand from the surface of the pattern, and the flask containing the mold is lifted vertically by a suitable crane. All of the foregoing procedure is a matter of common practice and need not be illustrated or 95 further described. It will be observed, however, that the side walls of the tub pattern 2 slope from the top portion or rims 9 and 10 to the bottom or supporting rib 8; and that on account of such sloping sides it is 100 not necessary for the workmen to remove the mold containing the flask in an absolutely vertical direction.

In order to form pockets in the mold, so that partition wings may be cast integrally 105 with the tub body, such partition wings being of substantially constant thickness throughout so that they may be readily

enameled, I provide a slot 14 in the wall of the tub pattern at such point as it is desirable to have the said wing formed, and I mount a plate 13 in such a manner that it is movable through the said slot 14, and so shaped that when in outward position it forms the desired wing pocket in the mold. The mold former shown herein is arranged to provide two of such pockets in the mold. 10 For each movable plate 13 a vertically disposed slot 14 is formed in the body of the tub pattern, and each plate is slidably mounted in suitable inclined tracks 15 and 16, secured to the pattern 2 and the ring 3, respectively. Each slot 14 preferably extends to a point adjacent to the outer edge of the rim of the tub, leaving a portion 17 of the rim connected for purposes of rigidity in the pattern. A plate-like projection 20 18 (see sectionally in Figs. 2 and 3) is formed on the said connecting portion 17, such projection being provided to fill in the space between the lower side of each plate 13 (when in outward position) and the adjacent side of the rim.

In order to move each plate 13 from one to another of its alternate positions, I preferably provide shafts 19, rotatably mounted in the frame 1; and to each shaft I secure a finger 20 having link connection to a plate 13. The said shafts may be turned by a suitable crank or handle (not shown) attachable to their outer ends.

In the operation of my mold former the 35 mold flask is placed in position around the pattern 2 in the usual and well known manner. The plates 13 are then moved to their outward positions (as is shown in the drawing) and the sand is packed about the pattern 2 and said extending plates. After the sand has been thoroughly packed in the usual manner the plates are withdrawn from the mold formed about them to their position within the tub pattern. It will 40 be understood that in their withdrawn position the plates are (as indicated in dotted lines in Fig. 2) completely within the pattern 2. While the said plates are being withdrawn each moves in its own plane, such movement being determined by the 45 tracks or guides 15 and 16; and the integrity of the mold adjacent to the wing pocket is maintained, the pattern 2 adjacent to each plate forming an effectual pro-

tection against the breaking down of the 55 mold.

I do not wish to limit myself to the details of construction shown herein for obviously many changes may be made by those skilled in the art without departing from 60 the spirit of my invention.

I claim herein as my invention:

1. In a mold former for bath tubs having integral outstanding partition wings, the combination of a tub body-pattern having 65 a slot in the side thereof extending from the bottom to the rim, a plate movable through said slot and when in outward position forming a partition-wing molding-member, and a plate-like projection extending outwardly from the rim portion of the 70 tub pattern adjacent to said slot, said projection being adapted to form a portion of a partition wing mold pocket.

2. In a mold former for bath tubs having 75 outstanding partition wings, the combination with a pattern supporting frame, of a tub body pattern having a slot in its side extending from the bottom to the rim, a plate movable through said slot, and a pair 80 of guideways for said plate one secured to said frame and one to said body pattern, said plate forming when in outward position a partition wing molding member.

3. In a mold former for bath tubs having 85 integral outstanding partition wings, the combination of a tub body pattern provided with a slot in its side extending from the bottom to a point adjacent to the outer edge of the rim of such pattern, the uncut portion of said rim adjacent to said slot rigidly 90 uniting the portion of said pattern adjacent thereto, a member movable through said slot and when in outward position forming a partition-wing molding-member extending 95 from the plane of the bottom of the body pattern to a point beneath the rim thereof, and a supplemental molding-member adapted to form the wing pocket from the end 100 of said movable member to the adjacent side of said rim when said movable member is in outward position.

In testimony whereof I have hereunto set my hand.

JOHN C. REED.
